US0D1039900S

(12) **United States Design Patent** (10) **Patent No.:** **US D1,039,900 S**
(45) **Date of Patent:** **** Aug. 27, 2024**

(54) **BARBECUE**

(71) **Applicant:** **Huizhou Haorui Hardware Technology Co., Ltd**, Huizhou (CN)

(72) **Inventors:** **Yong Zhang**, Huizhou (CN); **Chaosen Wang**, Huizhou (CN)

(73) **Assignee:** **Huizhou Haorui Hardware Technology Co., Ltd**, Huizhou (CN)

(**) **Term:** **15 Years**

(21) **Appl. No.:** **35/515,538**

(22) **Filed:** **Oct. 28, 2022**

(80) **Hague Agreement Data**

Int. Filing Date: **Oct. 28, 2022**

Int. Reg. No.: **DM/224489**

Int. Reg. Date: **Oct. 28, 2022**

Int. Reg. Pub. Date: **Nov. 11, 2022**

(51) **LOC (14) Cl.** **07-02**

(52) **U.S. Cl.**

USPC **D7/332**

(58) **Field of Classification Search**

USPC D7/323, 327, 328, 329, 332–337, 338, D7/339, 340, 341, 346, 347, 348, 350.1, D7/350.2, 350.3, 350.4, 352, 362, 365, D7/367, 402, 403, 404; D23/329, 338, D23/339, 342, 343, 402

CPC A47J 37/07–0763; A47J 37/0781; A47J 37/0786; A47J 37/0623; A47J 37/0658; A47J 2037/0777; A47J 33/00; A47J 2201/00; F24C 3/14; F24C 1/16; F24C 5/20; F24B 1/181; F24B 1/19; F24B

1/195; F24B 1/00; F24B 1/202–207; F24B 3/00; F23B 20/00
